UNITED STATES PATENT OFFICE.

RICHARD M. VAN EATON AND JULIA M. VAN EATON, OF PUEBLO,
COLORADO.

SWITCH-OPERATING DEVICE FOR STREET-RAILWAYS.

No. 802,538.

Specification of Letters Patent.

Patented Oct. 24, 1905.

Application filed June 19, 1905. Serial No. 266,007.

To all whom it may concern:

Be it known that we, RICHARD M. VAN EATON and JULIA M. VAN EATON, citizens of the United States, residing at Pueblo, in the county 5 of Pueblo and State of Colorado, have invented certain new and useful Improvements in Switch-Operating Devices for Street-Railways; and we do declare the following to be a full, clear, and exact description of the invention, such as will enable others skilled in the art to which it appertains to make and use the same.

Our invention relates to improvements in switch-operating devices for railways, adapted 15 to be operated by levers with which the cars are provided, so that the switch-operating devices may be controlled by a motorman or car-operator without the necessity of his leaving the car; and it consists in the construction, 20 combination, and arrangement of devices hereinafter described and claimed.

In the accompanying drawings, Figure 1 is a detail perspective view of our switch-operating devices mounted upon a portion of a 25 street-railway rail, the latter being shown partly in section to more clearly disclose our improved devices. Fig. 2 is a top plan view of a street-railway switch provided with switch-operating devices embodying our improvements. Fig. 3 is a perspective view, in 30 broken section, of a portion of the casting 6, the lever 3, and spring 25, showing clearly the relation of said spring to lever 3. Fig. 4 is a side elevation, in broken section, of the 35 front end of a street-car upon which is mounted the switching-cam and which is shown to be running upon a street-car track that is provided with our switching devices, the two 40 elements 13 and 12 of which are shown protruding above the rail. Fig. 5 is a front elevation of the switching-device cam ready to be mounted upon a car. Fig. 6 is a perspective view of a street-car rail and switch-point 45 about which is connected the complete switching device, the latter being housed by the castings 32 and 33.

Upon the rail 5 are securely bolted castings or supporting members 6 7 8, which are properly spaced apart and are adapted to receive the levers 1, 2, and 3, all of which are pivotally mounted on the casting 7. The lever 3 is on the outer side of the rail 5. The lever 1 is on the inner side of said rail, and the lever 2 is at a suitable distance from the

inner side of said lever 1. The rail has an 55 opening 24, and the lever 3 has a tappet 14, which is adapted to move through the said opening and to engage the outer side of the switch-point 4 to move said switch-point from the rail 5. The lever 1 has at its free end a 60 tappet 15, which is adapted to engage the inner side of the switch-point 4 to move the latter toward and against the switch-rail 5. The lever 2 is connected, by means of a rod 16, to the lever 3, said rod passing through the 65 opening 23 in the rail 5. The lever 1 is provided at one end with a wedge-shaped cam 13, which rises therefrom. A spring-arm 22 is secured to the under side of said lever 1 near its cam end and bears and operates on the casting or base member 8. A stop-block 20 is secured on the said base member in the path of the said spring-arm, its function being to limit the movement of the cam end of the lever 1 in one direction, the said spring-arm 70 serving to keep the cam end of said lever elevated. The fulcrum of said lever 1 is indicated at 10.

The lever 2 has at one end a cam 12, the oblique face of which is reverse to that of the 80 cam 13, said cam 12 being otherwise similar in construction to said cam 13. A spring-arm 21, which is secured to the under side of the lever 2 near its cam end, bears and moves on the base member 8, and the latter has a 85 stop-block 19, which serves by engagement with said spring-arm to limit the inner movement of the cam end of the lever 2.

The bolts which secure the base members to the under side of the rail 5 are indicated 90 at 17.

A spring 25, which is here shown as a coiled retractile spring, has one end 27 secured to the base 6 and the other end 26 secured to the free end of the lever 3. Said spring normally moves the free end of said lever outwardly to withdraw its tappet 14 from the switch-point 4, such movement of the lever causing the rod 16 to move the lever 2 to a 95 position parallel to said lever 3.

The spring-arms with which the levers 1 2 are provided by frictional contact with the base member 8 serve not only to elevate the cam ends of such levers, but also to prevent casual movement of said levers.

The housing shown in Fig. 6 is provided to secure the switching devices from ice, mud, and dust to a practical extent and may be re-

5 moved to enable the switching devices to be cleaned when the same becomes necessary. This housing device is secured in place by means of spikes which are driven into the 10 cross-ties. Said housing devices are provided with sheet-metal coverings 28 29, which are fitted on the cam ends 12 13 of the levers 2 1, respectively, said coverings being movable on the housing with said cam ends and serving 15 to cover the openings in the housing, which clear and permit said cam ends to move.

15 The levers 1 2 are operated by a cam 34, carried by the car. The said cam is adapted to be shifted laterally on the rod 39, which 20 serves to carry it, and will be initially set to engage either the cam 12 or the cam 13, according to whether the car is to proceed on one track or the other after passing the switch. Screws 38 secure the arms 35, which carry 25 said cam to the said rod 39. Said cam 34 may be raised or lowered by means of a bail 37 and a chain 36. The rod 39 has its bearing in brackets 40, which depend from the bottom of the car, said brackets being provided with 30 the braces 41.

30 To switch the car off the rail 5, the cam 34 will be set so that it will engage the cam 13 of lever 1 and cause said lever by means of its tappet 15 to move the switch-point 4 against the rail 5. If the cam 34 is set to engage the cam 12 of lever 2, the movement of 35 said lever 2 will cause the lever 3 to be also moved, so that its tappet 14 will engage the switch-point 4 and move said switch-point from the rail 5.

The chain 36 enables the cam 34 to be raised to pass over any object which may be on the track.

Having thus fully described our invention, 40 what we claim as new, and desire to secure by Letters Patent, is—

45 1. In combination with a switch-point, levers 1, 3, on opposite sides thereof and each having means to engage and move the switch-point therewith, said lever 1 having a cam at one end, a lever 2, having a cam at one end and opposite the cam of the lever 1, a link connecting the levers 2 and 3, to cause the

latter to move with the former, and a cam element carried by a car and movable into engagement with the cam of either of the levers 1, 2, substantially as described. 50

2. In combination with a switch-point, levers 1, 3, on opposite sides thereof and each having means to engage and move the switch-point therewith, said lever 1 having a cam at one end, a spring to move the lever 3 in one direction, means to limit the movement of the lever 1 in one direction, a lever 2 having a cam at one end and opposite the cam of the lever 1, a link connecting the levers 2 and 3, to cause the latter to move with the former, and a cam element carried by a car and movable into engagement with the cam of either of the levers 1, 2, substantially as described. 55 60 65

3. In combination with a switch-point, levers 1, 3, on opposite sides thereof and each having means to engage and move the switch-point therewith, said lever 1 having a cam at one end; a lever 2 having a cam at one end and opposite the cam of the lever 1, a link connecting the levers 2 and 3, to cause the latter to move with the former, yielding means coacting with each of the levers 1, 2, to prevent casual movement thereof, and a cam element carried by a car and movable into engagement with the cam of either of said levers, substantially as described. 70 75

4. A switch having a movable point, levers to move said point and having upwardly-extending cams for engagement and operation by a cam carried by a car, a housing covering the said levers and having openings to clear their cams, the latter projecting above the housing and closures for said openings, through which the cams extend and slideable on the housing and movable with and by the levers, substantially as described. 80 85 90

In testimony whereof we have hereunto set our hands in presence of two subscribing witnesses.
